(Cl. 66—48)

This invention is for improvements in and relating to the manufacture of hose (which expression includes stockings, three quarter hose and half-hose) and like articles knit in the main by rotation (and primarily those knit in substantially tubular form) but having at least one integral pocket or pouch; the invention also relates to the articles themselves and to a circular knitting machine for their manufacture. The invention is concerned with the production of the heel or toe, or both, in hose and with machines for knitting hose with such pockets. Heretofore in the production of hose and the like on a circular knitting machine, irrespective of whether such articles have been produced in truly seamless form or have been fashioned by an upwardly convergent gap at the back of the leg the edges of which are subsequently seamed together, it has been the usual practice to knit the leg and foot by relative rotation between the needle bed, and the knitting cams and the thread feeder, but to produce the heel and toe pockets by oscillation between the needle bed, and the knitting cams and thread feeder. The present invention provides a method and machine whereby the heel, or toe, or both may be knitted by rotation between said parts, and the expressions "rotation" and "rotary knitting" as hereinafter employed are employed to differentiate the invention from such oscillation.

Viewed from one aspect the invention provides in a method for the machine manufacture of a blank for a hose or the like mainly by rotary knitting which comprises fashioning the leg by the control of the number of needles in knitting activity to produce an upwardly converging gap in the back of the rotary-knit leg fabric, and producing heel parts united at their ends to the fabric of the back of the leg and of the foot bottom by knitting on two spaced groups of needles, one at each side of the gap left by inactive-leg-fashioning needles, while temporarily restraining instep needles, located between said groups, from knitting activity. The invention also includes a machine organised for the production of hose and like blanks mainly by rotation, having needles, including two spaced groups of heel needles with fashioning needles between said groups at one side and instep needles between them at the other, means for producing a fashioned leg by varying the number of fashioning needles in activity during rotary knitting and for thereby forming a tapering gap up the back of the leg fabric, and means for producing loops of heel fabric by temporarily restraining the instep needles from knitting activity while the two groups

of heel needles continue to knit. According to a subsidiary feature of the invention the toe is produced as a single tapering width of fabric by controlling the number of needles in knitting activity. 5 These needles which knit the toe may comprise instep needles as contrasted to the heeling needles which knit the heel pocket. The heel may be produced by causing the instep needles to hold their loops, continuing to knit on the heel needles during rotation, and finally re-introducing the instep needles into activity. In an alternative the heeling needles may knit by oscillation. As a result there is produced a band of heel fabric which is continuous with that of the leg and foot bottom and at its commencement and termination is united with successive courses of the instep but at its edges is disconnected from the instep. These edges therefore define holes in the fabric and will, according to the method of manufacture, be distinguished either cut end of yarn or floating thread, or will be selvedged. In the subsequent steps in the production of the finished hose or the like this band of fabric is severed from the foot bottom and the said edges are 15 united by linking or seaming to the initial course of the foot bottom (their length being the same as that of said initial course) and the cut edges of the heel band are seamed together. This latter seam may be continuous with the seam by which the edge of the fashioning gap are seamed together.

The invention further includes the articles of manufacture. The machine may embody the features claimed in any or all of the claims of U. S. Patents Nos. 2,105,965, 2,271,386, 2,290,147, 35 and 2,291,576 and/or described in the specifications of any one of these patents.

The foregoing and other features of the invention set out in the appended claims are incorporated in the examples now to be described with reference to the accompanying drawings, in which:

Figure 1 shows the stocking blank laid out flat, and also shows the needle and jack and the arrangement of butts thereon.

Figure 2 is a development of the cams and also illustrates the operation of certain pickers and shows a needle, a jack, and certain butts thereon.

Figures 3 and 4 show the needle cams and illustrate the manufacture of the heel loops by reciprocating and by rotary knitting respectively.

Figures 5 and 6 are plan views looking on top of the machine, each showing approximately one half of the circumference, and illustrating the arrangement of various knitting cams and needle pickers and sufficient of the controls therefor.

Figure 7 shows a battery of pickers employed in splicing and fashioning.

Figure 8 is a perspective view of a battery of pickers employed for mock-fashioning.

Figure 9 is a perspective view looking from underneath of a portion of the last said battery.

Figure 10 is an elevation showing the lower part of the needle cylinder, and illustrating the arrangement and control of picker mechanisms which operate on the jacks.

The machine according to this invention is in many respects similar to that described and illustrated in U. S. patent specifications Nos. 2,290,147 and 2,291,576 and so far as possible like reference numerals have been used. It is constructed and arranged to knit a stocking blank mainly by rotation but with a gap along the base of the foot and up the back of the leg, which gap has floating threads laid across it at each rotation of the machine and is tapered up the back of the leg to fashion said leg. In this blank the heel is produced, not in the form of a pocket as is customary, but in the form of two extra strip-like lengths of fabric, one at each side of the said gap, each of which is united at one end to the high heel and at the other end to the foot bottom and has its inner margin free from the instep fabric so that it protrudes as a kind of loop. When the stocking blank has been completed and removed from the machine the floating threads are cut out, the lower edges of each heel loop is separated from the initial course of the adjacent foot bottom, the inner margins of the heel loops are seamed to the initial courses of the foot bottom, and the edges of the blank are seamed together down the leg and along the foot, said seaming uniting the outer edges of the heel parts and the several courses thereof. The stocking thus produced bears a certain resemblance to a French foot stocking.

The needle cylinder is provided with a full complement of needles 11 having butts 12. These butts are of three different lengths. For example in a cylinder of 460 needles there is a central group of 80 long butt needles LB flanked at each side by a group of 40 short butt needles SB, while the remaining 300 needles SBX have extra short butts. Beneath each needle and working in the same trick there is a jack 33. These jacks have butts at eight different levels 34-40, the said butts being grouped as shown in Fig. 1. Each jack has a butt at level 40, the jacks TJ beneath the needles LB having long butts, the jacks FJT employed for fashioning the toe having medium butts, and the jacks FJL employed for fashioning the leg having short butts. Spaced jacks i. e. every second or third jack, has a picot butt at level 39, some of these picot butts being shorter than others to permit the insertion of a picot cam 45 hereinafter mentioned. At level 38 butts are provided on a leading group FJ of fashioning jacks that are located beneath the left-hand groups of needles SB and SBX, while at the rear end of said group a few jacks of group TJ have butts 38'. Similarly the right hand of trailing group of fashioning jacks FJ has butts 37 while a few of the adjacent jacks TJ have butts 37'; the said trailing group of jacks FJ likewise has butts 36. A right-hand group of splicing jacks SJ is provided with butts at level 35 and a left hand group of splicing jacks is provided with butts at level 34, while at the trailing end of the last-mentioned group a few jacks are provided with butts 34'. By means of these various jack butts the needles may be divided into two spaced

groups of heel needles HN with fashioning needles FN between them at one side and instep needles IN between them at the other side.

The knitting machine is preferably provided with two diametrically opposed knitting systems indicated at 1 and 2 in Fig. 2 in each system there being knitting cams of the conventional kind and a battery of interchangeable yarn feeders indicated respectively at F, F'. Those cams and other parts which are duplicated in each of the two systems have the same reference numbers and letters, those in system 2 being differentiated from those in system 1 by being primed. Thus in system 1 there are stitch cams 20 and 120 and guide cam 21 and if desired up pickers 22, 122 and down pickers 23, and 123, of the conventional kind. The corresponding parts in system 2 will be recognised, as for example, stitch cams 20', 120' and guide cam 21'.

At the termination of one stocking blank all the needles are in knitting activity their butts 12 traversing an active track 13. It is now necessary to press off all the needles with the exception of the central group LB. To do so cams 24, 25 and 26 are temporarily inserted. Cam 24 raises all the long butts LB above cam 26, cam 25 raises the needles SB and SBX to clear and the said needles are then lowered by cam 26 so as to pass down passageway 16 to an inactive track 14 and to press off their loops. Assuming that knitting is to proceed in system 2 all the movable cams are out of operation with the exception of clearing cam 120', the needles LB remaining in activity therefore clear at cam 120', take thread from the appropriate feeder of group F' and descend cams 21' and 20' to knit. A few roving and/or slack courses r are therefore produced on these needles, and it is then necessary progressively to introduce needles at either side of the active group so as to widen the toe t as shown in Fig. 1. This fashioning is effected by means of the toe fashioning jacks FJT, the butts 37 and 38, and the pickers 37a and 38a, 38b which are now rendered operative. These pickers and their operation areas described in U. S. patent specifications Nos. 2,290,147 and 2,291,576. Cam 42 is inserted to engage the long butts of jacks TJ so that the said butts thereafter follow the active track 16. Considering the right-hand group of fashioning jacks FJ, the butts 37 thereof will reach picker 37a at a lower level than the adjacent butts 37' and so the picker 37a is adapted to operate in known manner to pick the first butt reaching it and to elevate the butt 40 of said jack into the passage 18 so as to reach the active track 16. The butt 12 on the adjacent needle is thus passed up passage 15 from the inactive track 14 to the active track 13 so that the said needle thereafter knits. Considering the left-hand group of fashioning jacks, the butts 38' will, owing to the elevation of jacks TJ, reach the picker mechanism 38a, 38b at a higher level than the adjacent butts 38. The first control butt 38' strikes the driving arm 38a and swings the latter sideways, said arm drives the picker arm 38b which swings sideways, and upwards and picks the last butt 38 upwards, so that the corresponding needle is introduced into activity in the manner just described. This picking continues until all the jacks FJT have been picked and all the needles IN and HN are in activity, and is terminated by putting the picker mechanism out of operation. During the widening, however, mock fashion marks indicated at f may be pro-

duced parallel to the selvedge edges in a manner hereinafter described.

When the toe widening has been completed, knitting proceeds in both systems so that two courses are produced at each rotation. That is to say cams 20 and 120 together with the appropriate feeder of group F are introduced. A few unfashioned courses are made and then splicing commences to produce the spliced sole areas SS. This splicing involves the introduction of a splicing feeder in each of feeder groups F, F' and the jack cams 30, 30' which are adapted to raise certain needles higher than the corresponding clearing cams 120, 120' so that the needles thus raised take the splicing thread while the needles not so raised by cams 30, 30' take the main thread only, cams 120 and 120' being withdrawn and needle-clearing cams 24 and 29 inserted. It will be appreciated that by the toe widening operations all the splicing jacks SJ have been elevated into activity, the long butt jacks TJ having previously been raised by cam 42. Hence, unless measures are taken to prevent it, the splicing will initially be carried out on all the active needles. This may be prevented by lowering the jacks TJ by means of cam 28. If this step only is taken, the needles LB will not splice, but if before splicing commences of any required number of jacks at each end of group TJ are picked up again (by means 37a, 38a, 38b as hereinafter described for widening the spliced areas) some of the needles LB will splice. It is now desirable to narrow the spliced areas by progressively lowering the last jacks of the left-hand group SJ and the leading jacks of the right-hand group SJ. This is effected by down picker 35c and picker mechanism 34a, 34b (now placed in operation) in the manner described in the aforesaid patent specification. The first jack butt 35 strikes picker 35c and is lowered so that its butt 40 passes down the passageway 19 to the inactive track 17. The said jack therefore fails to be raised at the next rotation by cams 30', 30 and its associated needle will miss the splicing thread. Considering the left-hand group of jacks SJ, the butts 34 are at a somewhat higher level than the trailing butts 34'. The latter strike the driving arm 34a and swing it sideways. This causes the picking arm 34b to swing sideways and downwards to lower the last butt of group 34 and thereby to lower the associated jack and to prevent the associated needle from splicing. These operations proceed until the spliced areas SS are reduced to the desired width when the splicing pickers are rendered inoperative and rotary knitting continues. Subsequently just before the heel it is necessary to widen the spliced areas slightly. This widening is effected by means of butts 34 and 35, picker 34c and picker mechanism 35a, 35b (now placed in operation) as described in the aforementioned patent specification. By mechanism 34a, 34b the butts 34 have been divided into a raised leading sub-group and a lowered trailing sub-group. The first butt of the trailing sub-group strikes picker 34c and is picked up so that the associated needle resumes splicing activity. By the operation of picker 35c the group 35 has been divided into a low leading sub-group and a raised trailing sub-group. The first butt of the trailing sub-group strikes arm 35a and swings it sideways to cause arm 35b to swing sideways and upwards and to pick up the last butt of the leading sub-group thereby causing the associated needle to resume splicing activity.

When the splicing has been widened (desirably until it extends into the instep needles IN so that the corners of the heel are reinforced) at the termination of the foot S the pickers are rendered inoperative and it is now necessary to produce the heel parts h. The said parts may be knitted either by reciprocation or by continued rotation.

If the heel parts h are to be produced by reciprocation, cam 44 is momentarily inserted to raise the instep needles IB (having butts LB and SB) to a high loop-holding level (Fig. 3) leaving only the two groups of heel needles HN active.

All the movable cams except 20 and 120 are retracted, the machine comes into reciprocation in known manner and the up pickers 22, 122 and the down pickers 23' and 123' are rendered operative. The two groups of needles HN therefore continue to knit at system I (floats being laid across the gap left by needles FN) but at each swing the inner end needles of these groups are raised by pickers 22 and 122 and lowered by pickers 23' and 123' so that the fed thread wraps around them and a good selvedge is produced. When the requisite number of heel courses has been knitted (i. e. when the length of each heel part is at least equal to its width) the pickers are rendered inoperative, cam 120 is retracted and cam 20' is inserted; cam 32 is introduced to return the instep needles IN to activity and the machine changes over to rotary knitting.

If the heel loops or strips h are to be produced by rotary knitting then the pickers 22, 122 etc. are either omitted from the machine or are not utilised. Instead of cam 120, bolt cams 120a, 120b, Fig. 4, are provided. The cam 120a is fully inserted but the cam 120b is introduced only sufficiently to engage the butts SB and LB. Therefore said cam 120b lowers all the needles IN so that they pass beneath cam 120a and neither take the thread nor clear their loops, but the heel needles HN are raised by cam 120a to clear their loops and take the fed thread. In this mode of heel production floating threads are produced across the gap left by the inactive needles IN between the adjacent inner edges of the heel parts and also across the gap left by the inactive needles FN between the outer edges of said heel parts.

As soon as the heel has been completed the various splicing cams are re-introduced and the spliced areas are again narrowed to a predetermined width (in the manner before described) and splicing then continues for the high heels hs. At the top of the high heel parts hs the splicing feeders and the clearing cams 24 and 29 are withdrawn. The active jacks TJ and FJT continue to be raised by cams 30, 30' so that their needles clear, said needles knitting at stitch cams 20 and 20'. This rotary knitting continues until it is necessary to fashion the leg.

The leg fashioning is effected in the same manner as the toe fashioning already described and results in the jacks FJL and the associated needles FN being introduced into activity so as gradually to narrow the gap extending up the back of the leg. This fashioning is preferably accompanied by the production of lines of mock fashion marks f parallel with the edges of the blank. In producing these mock fashion marks selected jacks are depressed so that their butts 40 pass under the clearing cam 30 and traverse the track 16a which leads them under the other clearing cam 30'; the said butts then re-enter the active track 16. As a result the associated needles tuck

for two courses. The mock fashioning is effected by picker mechanisms 36a, 36b, 38a', 38b' in a manner similar to that described in the aforementioned specification. At this stage the jacks FJT and TJ are raised and active and the jacks FJL are lowered and inactive. Considering first the production of the mock fashion marks at the right-hand edge of the blank (Fig. 1) it will be apparent from the disposition of the cam tracks 16, 17 beneath the mock fashioning picker mechanism that the butts 37 of the raised active jacks FJT approach said mechanism at a higher level than do the butts 36 of the inactive jacks FJL. In other words there is a raised leading sub-group of butts followed by a lower trailing sub-group of butts. At each course in which the mechanism 36a, 36b is rendered active the first butt for the time being of the trailing sub-group strikes the arm 36a and swings it sideways. By this movement the arm 36b is swung sideways and lowered so that at least one butt slightly in advance of the trailing end of the leading sub-group is picked downwards. The butt 40 of each jack thus picked downwards is passed beneath the clearing cam 30 so that the associated needle tucks for the two courses as just described. Since by the operation of the fashioning picker 37a butts are progressively added to the trailing end of the leading sub-group and other butts are progressively removed from the leading end of the trailing sub-group, the resultant line of tuck stitches is parallel with the fashioned edge.

In the case of the fashion marks at the left-hand edge of the blank (Fig. 1) it will again be appreciated that the butts 38 on the inactive jacks FJL are at a lower level than the butts 38 of the active jacks FJT and by the operation of the fashioning picker mechanism 38a, 38b butts 38 are progressively added from the trailing end of the low leading sub-group to the trailing end of the high leading sub-group. At each course in which the mock fashioning mechanism 38a', 38b' is operative, the first butt for the time being of the trailing sub-group strikes arm 38a' and swings it sideways. This movement causes the arm 38b' to swing sideways and downwards and the said arm therefore lowers at least one butt spaced slightly to the rear of said leading end. The butt 40 of each jack thus picked down passes beneath the clearing cam 30 and the associated needle tucks for two courses in the manner described.

It may be here mentioned that the mock fashion marks *f* in the toe *t* are produced in a similar manner. In the case of the right-hand line of marks, initially the butts 37' of the active jacks TJ form the leading sub-group and the butts 36 of the inactive jacks FJ form the trailing sub-group. In the case of the left-hand line of fashioning marks the butts 38' of the active jacks TJ form the trailing sub-group to which butts 38 of jacks FJT are progressively added.

At a subsequent stage in the tubular knitting, after all the needles have been rendered active, it is desirable to produce a picot edge. The needle cams 20' and 120' and the jack cam 30' are withdrawn for four courses during which the needles clear at cam 30 and knit at cam 20. Picot cam 45 is moved inwards to engage the spaced jack butts 39. The butts 40 of the jacks that are thus lowered pass beneath cam 30 and the associated needles tuck. Subsequently needle cams 120, 120' are inserted, and jack cam 28 is pushed in so that all the jacks are lowered to the inactive position.

If it is desired to make an ordinary toe pouch by reciprocation, at the commencement of the stocking only the needles SBX are pressed off, as may readily be effected by pushing cam 24 in sufficiently to raise needles SB as well as needles LB. During rotary knitting, cam 21 is slightly withdrawn and cam 31 inserted. All the active needles HN and IN are raised by cam 120, but the needles HN, having extra short butts, miss cam 21 and pass round to cam 31 by which they are elevated to the inactive loop-holding position. The needles IN, having long and short butts, are lowered by cams 21 and 20 and therefore remain in activity, and the toe pouch may be knitted, by reciprocation, on these needles at either of the two knitting systems: preferably in system 2 as described in the aforementioned U. S. Patent specifications Nos. 2,290,147 and 2,291,576.

It will be appreciated that any desirable yarn changes may be effected during the knitting of the stocking blank, as for example for the production of a stout welt fabric.

The battery of pickers beneath system 2 is shown in Fig. 7. This battery consists of a body 50 carrying a vertical spindle 51 about which picker blocks 52a, 52b, 52c and 52d are pivoted. The block 52a has picker arm 34c pivoted to it for movement about a horizontal axis 53a, and for said arm there is a guide plate 54a and a return spring 55a. The block 52b, provided with return spring 55b, carries the arm 35a and also has pivoted to it, for movement about a horizontal axis, 53b, the up picker 35b. For said picker 35b a guide plate 54b is provided. The block 52c has picker arm 37a pivoted to it for movement about horizontal axis 53c, and said arm is provided with guide plate 54c and return spring 55c. The block 52d, provided with return spring 55d carries arm 38a and has picker arm 38b pivoted to it for movement about a horizontal axis 53d, said arm being provided with guide plate 54d. The various pickers may be moved to and from operative positions by arms projecting radially from their blocks. Thus block 52a carries control arms 56a; block 52b, arm 56b; block 52c, arm 56c; and block 52d, arm 56d.

The various picker mechanisms shown in Fig. 2 are controlled from a racking pin drum 80 (Fig. 10) surrounding the base of the needle cylinder 10. Picker 34c and mechanism 35a, 35b, are swung to and from operative position by a rock lever 81 engaging pins 56a, 56b, and connected to a feeler 85 for the pin drum 80. Picker 37a and mechanism 38a, 38b are controlled by rock lever 88 engaging pins 56c, 56d and connected to feeler 90.

The picker mechanisms 34a, 34b and 35c arranged beneath knitting system 1 are substantially similar respectively to the mechanisms 35a, 35b and 34c, and therefore need no further illustration than is provided by Figs. 7 and 10, but it may be pointed out that whereas picker 34c is an up picker and is located above mechanism 35a, 35b, the splicing narrowing picker 35c is a down picker and is located beneath mechanism 34a, 34b. For mechanism 34a, 34b there is a control pin 56b and for picker 35c a control pin 56a. The rock lever is indicated at 81 and the feeler at 85.

The battery of mock-fashioning pickers 36a, 36b, 38a, 38b located in advance of knitting system 1 is shown in Figs. 8 and 9. There is a body 57 carrying two parallel vertical spindles 58 and 59. Arm 36a projects from a block 60a rotatably mounted on spindle 58. Said block is connected,

to a block 60b rotatably mounted on spindle 59, by means of connection 61. The picker arm 36b is mounted on block 60b for movement about horizontal axis 62a and is provided with a guide plate 63a and a return spring 64a; said block 60b likewise has a control arm 65a. Arm 38a is attached to block 66a rotatably mounted on spindle 59 and connected by a connection 61b to block 66b rotatably mounted on spindle 58. Block 66b has picker arm 38b pivoted to it for movement about a horizontal axis 62b and is provided with a return spring 64b. Block 66a has a control arm 65b. Pins 65a, 65b are engaged by rock lever 92 connected to feeler 94.

The mock-fashioning picker mechanism 36a, 36b, and 38a, 38b in advance of knitting system 2 is similar to that just described and illustrated and needs no further description herein. It is indicated generally at 57 in Fig. 10.

In general the connections whereby the various cams and other mechanisms hereinbefore referred to are controlled from a suitable control member such as the main drum of the machine or a chain or drum, may follow standard practice in knitting machines and little description and illustration thereof is necessary herein, for once the functions of such parts have been described numerous simple controls for them will present themselves to a knitting machine builder without the necessity for invention. Figs. 5 and 6 show the lay-out of the knitting cams and needle pickers. Each said figure is a plan view dealing with approximately half the circumference of the machine. Fig. 5 relates to knitting system 1 and Fig. 6 to system 2, and in the two figures parts which are duplicated for the two systems (or are mechanical equivalents) are given the same reference numbers, but those in Fig. 6 for system 2 are differentiated by a dash. Dealing first with system 1 the yarn feeders F are controlled in customary manner by a battery of push rods 10.

Cams 24 and 25 are operated by a common bell-crank-lever 24b from bell-crank 24c and thrust bar 24d. Outwardly extending slide parts of these cams are slotted at 24e to accommodate a compression spring 24f, half in each slot, while a stronger spring 24g extends from cam 24 to a slide 24h on which the lever 24b operates. A first inward movement of 24h carries cam 25 inwards to the cylinder and a second inward step of 24h overcomes the compression spring 24f and carries cam 24 into the cylinder. Down picker 23 is idled by bell-crank-lever 75 and thrust bar 76, and cam 31 is controlled by bell-crank 89 and thrust bar 89a. The up pickers 22 and 122 are connected by a link 22a in a manner customary in B5 machines, whereby when one is operable the other is idle and the displacement of one picker by a butt swings the other into operative position. They are both idled by a bell-crank-lever 72 and a thrust bar 72a. Rigidly projecting from the thrust bar 72a there is an arm 72b which projects beneath the horizontal arm of a bell-crank-lever 70a, the vertical arm of which is connected to cam 21 by a link 70. An adjustment screw 70b at the top of the vertical arm of the bell-crank-lever 70c overlies the said horizontal arm of bell-crank-lever 70a. The bell-crank-lever 70c is pivoted to the machine frame and its horizontal arm is pivoted to a member 70d depending rigidly from the arm 72b that projects from the thrust bar 72a. This mechanism ensures that when the cam 21 is introduced it cannot slip out. Cam 120 has a pin 120a projecting from its slide through a slot 120b in the platform of the machine, which pin

is movable along the slot by lever 120c and thrust bar 120d; cam 20 is similarly operated. Down picker 123 is idled by bell-crank-lever 175 and thrust bar 176, and cam 29 is operated by lever 86, bell-crank-lever 86a and thrust bar 87.

The foregoing parts are in general duplicated in Fig. 6 with reference numerals with a dash, but in this case the up pickers 22' and 122' are not interconnected as are the pickers 22, 122 but are provided with their respective idling levers 72' and 172' operated by thrust rods. Cam 32 is controlled by pin 32a projecting from its slide bar and a bell-crank-lever 32d operated by a thrust bar 32c. Cam 26 is controlled by bell-crank-lever 67 and a thrust rod, and cam 44 by bell-crank-lever 69' and a thrust rod.

We claim:

1. A method for the machine manufacture of a blank for a hose or the like mainly by rotary knitting, which comprises fashioning the leg by the control of the number of needles in knitting activity to produce an upwardly converging gap in the back of the rotary-knit leg fabric, and producing heel parts united only at their ends to the fabric of the back of the leg and of the foot bottom by knitting a strip of fabric on each of two spaced groups of needles, one at each side of the gap left by inactive leg-fashioning needles, while temporarily restraining instep needles, located between said groups, from knitting activity.
2. A method for the machine manufacture of a blank for a hose or the like mainly by rotary knitting on a machine comprising a group of instep needles, a group of heel needles flanking it on each side, and fashioning needles opposite the instep needles between the two groups of heel needles, which comprises knitting on a progressively increasing number of needles to form a toe as a single tapering width of fabric, said knitting being continued until the two groups of heel needles and the group of instep needles are active but the fashioning needles are inactive; knitting a foot by rotation on said heel and instep needles while laying floats across the gap left by the inactive needles; producing heel parts by continuing the heel needles in activity while the instep needles hold their loops; returning the instep needles to activity and continuing rotary knitting on the heel and instep needles with the formation of floats across the gap and, during said rotary knitting, progressively introducing the hitherto-inactive needles into activity at each side of the gap to form a fashioned leg.
3. A circular knitting machine organised for the production of hose and like blanks mainly by rotation, having needles, including two spaced groups of heel needles with fashioning needles between said groups at one side and instep needles between them at the other, means for producing a fashioned leg by varying the number of fashioning needles in activity during rotary knitting and for thereby forming a tapering gap up the back of the leg fabric free at their edges but united only at their ends to the fabric of the back of the leg and of the foot bottom, and means for producing strips of heel fabric by temporarily restraining the instep needles from knitting activity while the two groups of heel needles continue to knit.
4. A machine according to claim 3, in which the heel fabric is knitted by reciprocation on a constant number of needles of the heel groups and having means for diverting the instep needles

to and from a loop-holding level at which they remain during the reciprocation.

5. A machine according to claim 3, in which both heel groups reciprocate past and take thread from the same feeder.

6. A machine according to claim 3, having means for temporarily elevating, in each swing, the inner end needle of each heel group so that the fed thread wraps round it.

7. A machine according to claim 3, in which the heel fabric is knitted by rotation, having a clearing cam at which the heel needles rise to take thread and means for diverting the instep needles below said cam.

8. A machine according to claim 3, incorporating means for knitting a toe as a single tapering width of fabric by progressively introducing instep and heel needles into knitting activity.

9. A machine according to claim 3, having two knitting systems for knitting two courses at each revolution.

10. A circular knitting machine adapted to knit a hose or like blank mainly by rotation, having a needle cylinder and a circular complement of needles therein, the number whereof and the diameter of the circle being that for the production of a single blank in substantially tubular

form and said needles comprising a group of fashioning needles and a group of instep needles disposed over substantially diametrically opposed parts of the circle and two groups of heel needles 5 interposed between the aforesaid groups, two circumferentially spaced sets of knitting cams and thread feeding means, an active cam track for conducting the needles through each set of cams in turn during rotary knitting so as to produce two courses at each rotation, an inactive track for conducting needles past both sets of cams without knitting, fashioning mechanism for progressively changing instep and heel needles from the inactive to the active track in the production of a tapered toe and for progressively changing fashioning needles from the inactive to the active track during rotary knitting in the production of a fashioned leg, and means for temporarily suspending knitting on the instep needles 10 while continuing knitting on the two groups of heel needles to produce two lengths of heel fabric each separate at its edge from the instep fabric but united top and bottom with the leg fabric and foot bottom fabric.
